[57] CLAIM

The ornamental design for a tape spool, as shown and described.

DESCRIPTION

FIG. 1 is a perspective view of a tape spool showing my new design;

FIG. 2 is a top plan view thereof;

FIG. 3 is a front elevational view with the rear view being identical thereto and the roll of tape shown being for illustrative purposes only and forming no part of the claimed design;

FIG. 4 is an elevational view of a first side thereof, the opposite side elevational view being identical thereto; and,

FIG. 5 is a bottom plan view thereof.
